CLAIM

The ornamental design for a firearm accessory mount rail, substantially as shown and described.

DESCRIPTION

FIG. 1 is a perspective view of a firearm accessory mount rail according to one embodiment of my new design viewed from above, behind, and a right side thereof.

FIG. 2 is a rear side elevation view thereof;

FIG. 3 is a front side elevation view thereof;

FIG. 4 is a right side elevation view thereof;

FIG. 5 is a left side elevation view thereof;

FIG. 6 is a top plan view thereof; and

FIG. 7 is a bottom plan view thereof;

FIG. 8 is a perspective view of a firearm accessory mount rail according to another embodiment of my new design viewed from above, behind, and a right side thereof;

FIG. 9 is a rear side elevation view thereof;

FIG. 10 is a front side elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The dot-dash broken lines shown in the drawings represent imaginary boundary lines such that the claimed design extends to the boundary but does not include the boundary. The uniformly broken lines outside the imaginary boundary lines show portions of the firearm accessory mount rail that form no part of the claimed design.
